O. THIEME.
RIBBON REVERSING MECHANISM.
APPLICATION FILED MAY 20, 1916.

1,245,637.

Patented Nov. 6, 1917

UNITED STATES PATENT OFFICE.

OTTO THIEME, OF ST. LOUIS, MISSOURI, ASSIGNOR TO MOON-HOPKINS BILLING MACHINE COMPANY, OF ST. LOUIS, MISSOURI, A CORPORATION OF MISSOURI.

RIBBON-REVERSING MECHANISM.

1,245,637.

Specification of Letters Patent.

Patented Nov. 6, 1917.

Application filed May 20, 1916. Serial No. 98,854.

To all whom it may concern:

Be it known that I, OTTO THIEME, a citizen of the United States, residing at the city of St. Louis, State of Missouri, have invented a certain new and useful Improvement in Ribbon-Reversing Mechanism, of which the following is a full, clear, and exact description, such as will enable others skilled in the art to which it appertains to make and use the same, reference being had to the accompanying drawings, forming part of this specification, in which—

Figure 1 is a plan view of my improved ribbon reversing mechanism.

Fig. 2 is a rear elevational view of the same.

This invention relates to a new and useful improvement in ribbon reversing mechanism designed especially for use in connection with combined adding and typewriting machines and particularly in connection with a tally-roll attachment for such machines disclosed in a companion application executed and filed by me of even date here-with, and serially numbered 98,853.

The object of my present invention is to provide a simple and effective ribbon reversing mechanism which enables the use of the entire length of the ribbon and as the ribbon becomes exhausted from one spool, the winding mechanism therefor will be automatically reversed whereby the ribbon will be wound on the empty spool.

In the companion application referred to, the parts of the adding mechanism are motor driven and therefore there is ample power to operate the parts of my reversing mechanism.

While my present improvement may be useful in connection with typewriting machines, wherein power, derived from manually operated key pressure, is relied upon to operate the ribbon reversing mechanism, I do not recommend its use in such machines because when the ribbon becomes exhausted from one spool, and the reverse mechanism is brought into play, the power necessary to operate it, being appreciable, will be felt by the operator, and might constitute a disturbing element in the operation of the machine.

In the drawings 593 indicates a rock arm which is vibrated by suitable power operated means and by virtue of this vibration and pawl and ratchet mechanism operated thereby, the shaft 599 mounted in suitable

bearings on the framing of the machine is caused to be rotated a short distance at each vibration of the arm 593 to effect a feeding action of the ink ribbon.

600 indicates an ink ribbon which, as shown in Fig. 1, is designed to be wound upon spools 601. Each of these spools has a miter gear 602 connected thereto with which miter gears 603 are designed to alternately engage, depending upon the direction of feed of the ribbon—the ribbon being taken up or wound upon the spool which is being driven. The shaft 599, before referred to, is of such length that when one of these gears 603 is in driving engagement with one spool, the other of said gears is out of driving engagement, and vice versa. Each of the ribbon spools 601 has a hollow core formed in part by a fixed curved wall 604, to which the ends of the ribbon may be secured, and a movable wall 605, the latter being pivoted at one end and connected to a spring 606 which tends to open said wall, as shown at the right in Fig. 1. The free end of this swinging wall carries a pin 607 which extends down through a curved slot in the bottom spool head. In the position of the parts shown in Fig. 1, the pin 607 has been permitted to move outwardly, into the path of a hook on the end of a sliding bar 608. Up to this time, the spool at the right-hand end, in Fig. 1, has been positively driven and exhaustion from the spool at the left-hand side of said figure has permitted the outward swinging of the removable wall 605 and the location of the pin in front of the hook. The continued rotation of the left-hand spool in the direction of the arrow, by the drawing off of the ribbon, will cause the pin 607 to slide the bar 608 leftwardly, moving the pinion 603 out of driving engagement with the right-hand spool and the pinion 603, at the left, into engagement with the spool at the left. The spool at the left now becomes the driven spool and in winding up the ribbon thereon, its rotation will be reversed from that indicated by the arrow and the ribbon will in due course fold in the movable wall so as to locate the pin 607 out of the path of the hook on the end 105 of the bar 608. The bar 608 has a hook on its opposite end and the spool at the right side of Fig. 1 has a fixed and movable wall, above described. The bar 608 has an upward extension carrying two collars 609 110

slidingly mounted on the shaft 599. Between these collars and members affixed to the shaft are springs 610, one of said springs being interposed between each collar and a fixed member of the shaft. The purpose of this yielding connection is to take care of any cogging of the teeth between gears 603 and 602. If the gears are cogged, that is, not brought into proper registration when the bar 608 is moved, one of the springs 610 will be compressed until by the next rotation of the shaft 599, the teeth of the gears are brought into proper mesh.

There is a centering device for holding the shaft 599 in its two positions, this consisting of the bar 611, having a roller on its upper end which drops into either one of two V-shaped grooves 612, cut in the shaft 599. A spring 613 holds this roller against the shaft (see Figs. 1 and 2). The ink ribbon 600 passes over vertically disposed guide rollers 614 and angularly disposed guide rollers 615. The ribbon is guided by suitable guides over the type in the printing line on the type segments 561.

In Patent No. 996,164, dated June 27, 1911, granted upon an application filed by me, will be found a ribbon reversing mechanism on which this is intended as an improvement in so far as the present device has a fewer number of parts and is more simple in its construction and operation.

In the present device, the shaft 599 slides in its bearings a short distance and in this way the clutches shown in the former patent are dispensed with.

I claim:

In a device of the character described, a ribbon reversing and rewinding mechanism comprising a ribbon reel mounted on each side of the machine, said reel having cores, a shaft extending between the reels and designed to alternately engage and drive said reels, means for holding said shaft in different positions, and a shaft shifting mechanism comprising movable spring held sections constituting parts of the walls of the reel cores, the free edges of said sections having lateral projections extending through slots in the reel-walls, and a sliding bar having hooks or shoulders at each end adapted to be engaged and operated by said lateral projections when the movable sections of the core are swung outwardly by their springs respectively when a reel is unwound.

In testimony whereof I hereunto affix my signature in the presence of two witnesses, this 11th day of May, 1916.

OTTO THIEME.
